UNITED STATES PATENT OFFICE.

GEORGE W. HOWES, OF DOWAGIAC, MICHIGAN, ASSIGNOR TO THE BECKWITH COMPANY, OF DOWAGIAC, MICHIGAN.

COMBINATION SOLID-FUEL AND GAS RANGE OR COOKING-STOVE.

1,355,338.

Specification of Letters Patent.

Patented Oct. 12, 1920.

Application filed October 26, 1918. Serial No. 259,747.

To all whom it may concern:

Be it known that I, GEORGE W. HOWES, a citizen of the United States, residing at Dowagiac, county of Cass, State of Michigan, have invented certain new and useful Improvements in Combination Solid-Fuel and Gas Ranges or Cooking-Stoves, of which the following is a specification.

This invention relates to improvements in combination solid fuel and gas ranges or cooking stoves.

The main objects of this invention are:

First, to provide in a combination solid fuel and gas range or cooking stove an improved oven structure which is very effectively heated either by solid fuel, such as coal, or wood or by gas.

Second, to provide an improved combination solid fuel and gas range or stove which 20 may be conveniently converted from one to the other.

Further objects, and objects relating to structural details, will definitely appear from the detailed description to follow.

25 I accomplish the objects of my invention by the devices and means described in the following specification. The invention is clearly defined and pointed out in the claims.

30 A structure which is a preferred embodiment of my invention is clearly illustrated in the accompanying drawing, forming a part of this specification, in which:

Figure I is a detail front perspective view 35 of a structure embodying the features of my invention, with the oven adjusted to be heated by solid fuel.

Fig. II is a front perspective view of my 40 improved stove adjusted to heat the oven by gas.

Fig. III is a perspective view of the base of my improved stove showing the support for the burner plate and burner when not in use, the support being released and the 45 burner plate in position as discharged therefrom.

Fig. IV is a perspective view of the base with the burner plate supported therein.

Fig. V is an enlarged detail vertical section on a line corresponding to line 5—5 of Fig. IV, showing the latch for the burner plate support.

Fig. VI is an enlarged detail vertical section on a line corresponding to line 6—6 of Fig. V, with the burner in position in the

oven, the burner coupling being shown in operative position by dotted lines and in retracted position by full lines, the operating mechanism being shown in full lines.

Fig. VII is an enlarged detail section 60 through the burner and burner plate and the gas coupling, showing the coupling in operative relation to the burner.

Fig. VIII is a detail bottom view of the air damper and its operating connection. 65

In the drawing similar reference characters refer to similar parts throughout the several views, and the sectional views are taken looking in the direction of the little arrows at the ends of the section lines. 70

Referring to the drawing, 1 designates the stove body generally and 2 the base which is provided with legs 3.

I desire to point out that I have not, in the accompanying drawing, attempted to 75 maintain the relative proportion of the parts, nor have I attempted to show structural features of the body proper nor the joints or connections for its several parts, as such details will be readily understood by 80 those skilled in the art to which my invention relates.

The oven 4 in the structure illustrated is positioned as is common practice. The firepot and ashpit are at the left hand but, as 85 these details form no part of this invention, I have not illustrated them herein. The flue from the firepot extends over the top of the oven, downwardly at 3' and under the oven at 4, this flue arrangement being well-known in the art. 90

The bottom 5 of the oven is provided with a central opening 6. The bottom 7 of the flue has an opening 8 aligned with the opening 6. An air flue 9 in the heating flue connects these openings 6 and 8. The bottom of the oven forms the top wall of the heating flue. 95

A gas delivery pipe 10 is arranged under the heating flue and has a vertical delivery portion 11 disposed centrally of the air flue 9. Below the air flue is a damper box 12 having damper openings 13 controlled by the damper 14 pivoted at 15. The burner 16 is mounted on the under side of the burner plate 17 which is removably mounted in the oven so as to support the burner in a spaced relation to the bottom of the oven and the burner plate with its edges in a spaced relation to the walls of the oven. 100 105 110

In the structure illustrated the burner plate is supported by the arms 18 which engage the shelf ledges 19 of the oven. The burner is preferably mounted for limited vertical movement, being mounted, in the structure illustrated, on the headed pins 20 which engage lugs 21 on the burner.

The burner has lugs 22 which limit its movement toward the plate. The burner, in the structure illustrated, has a central cross portion 23 with a chamber or passage therein communicating with the chambered rim portion 24 having jet orifices therein. The burner is provided with a downwardly facing conical seat 25 adapted to receive the conical head 26 of the coupling member 27 slidably mounted on the vertical portion 11 of the supply pipe. This coupling member is adapted to be projected through the opening 6 or retracted into the air flue and engages the seat so as to make an effective joint and also the burner being loosely mounted may be lifted by and partially supported on the coupling member, thus insuring a perfect connection and also accommodating for irregularities in manufacture and any warping or displacement of the parts that might occur in use.

The opening 6 is provided with a removable cover or closure 28. The gas coupling member, in the structure illustrated, is actuated by the lever 29 which is pivoted at 30 and slotted at 31 to receive a pin 32 on the collar 33 of the coupling member, the collar being threaded upon the coupling member to provide for convenient adjustment of the coupling member.

The actuating lever 34 is pivoted at 35, the pivots 30 and 35 being preferably mounted on the gas supply pipe 10 and connected with the lever 29 by a ball and socket connection shown conventionally at 36.

The damper 14 is connected by the link 37 to an arm 38 on the lever 34, so that by the actuation of the lever the damper is opened and closed and also the burner is connected and disconnected with the gas supply. The gas delivery pipe 10 is, in the structure illustrated, a Bunsen tube, the gas being delivered thereto by the pipe 39 controlled by the valve 40. This valve, which is located at the rear of the stove, has an actuating shaft or rod 41 extending to the front of the stove and provided with a hand-piece and index 42' which not only indicates when the valve is in its closed position, but also the degree of opening of the valve. To insure connection to the burner when the valve is opened the shaft 41 is provided with a crank 42 which engages a slot 43 in a bar 44 connected at its lower end to the end of the lever 34 and slidably supported at its upper end. With this arrangement the valve cannot be opened without the gas coupling member being projected into the oven.

As a convenient means of supporting the burner plate and burner when removed from the oven I provide a rack 45 pivoted within the base of the stove at 46, its front end being supported by the automatically engaging latch 47. The burner plate may be arranged on this rack in an inverted position and the rack swung up to the position shown in Figs. IV and V, so that it is entirely concealed and out of the way. A push on the latch 47 with the foot releases the rack so that its front end drops down as shown in Fig. III and the burner plate slides out under the base and can be readily picked up and shoved into the oven.

For convenience in lighting the burner I provide a pilot 48, the front end of which projects through a flange 49 on the front edge of the burner plate.

My improved combination solid fuel and gas stove is very efficient both when used with solid fuel and when used with gas. The structure is easily adapted for the use of either fuel. I have illustrated and described my improvements in one form in which I have embodied the same for the market. I have not attempted to illustrate or describe other embodiments or adaptations as I believe the disclosure made will enable those skilled in the art to which my invention relates to embody or adapt the same as may be desired.

Having thus described my invention, what I claim as new and desire to secure by Letters Patent, is:

1. A combination stove comprising an oven, a heating flue extending below said oven, the bottom of the oven constituting the top of the flue, an air flue disposed centrally below said oven, the oven bottom having an opening above said air flue, said opening being provided with a removable cover, a damper box provided with a damper disposed below said heating flue to embrace the lower end of said air flue, a burner plate removably supported in said oven in spaced relation to its bottom and with its edges in a spaced relation to the oven walls, a burner mounted on the under side of said burner plate for limited vertical movement and having a centrally disposed downwardly facing tapered coupling member seat, a gas supply pipe disposed below said heating flue and provided with a vertical delivery portion disposed in said air flue, a coupling member slidably mounted on said delivery portion of said pipe and provided with a conical head adapted to coact with said coupling seat of said burner when the coupling member is elevated, a coupling member lever pivotally mounted on said pipe and having a pin and slot connection with said coupling member whereby the coupling member is raised and lowered by the actuation of said lever, an actuating lever mounted on said

gas supply pipe and having ball and socket connection with said coupling member lever, a link connecting said actuating lever to said damper, a gas supply valve, and operating connections from said gas supply valve to said actuating lever.

2. A combination stove comprising an oven, a heating flue extending below said oven, the bottom of the oven constituting the top of the flue, an air flue disposed centrally below said oven, the oven bottom having an opening above said air flue, said opening being provided with a removable cover, a damper box provided with a damper disposed below said heating flue to embrace the lower end of said air flue, a burner plate removably supported in said oven in spaced relation to its bottom and with its edges in a spaced relation to the oven walls, a burner mounted on the under side of said burner plate for limited vertical movement and having a centrally disposed downwardly facing tapered coupling member seat, a gas supply pipe provided with a vertical delivery portion disposed in said air flue, and a coupling member slidably mounted on said delivery portion of said pipe and provided with a conical head adapted to coat with said coupling seat of said burner when the coupling member is elevated.

3. A combination stove comprising an oven, a heating flue extending below said oven, the bottom of the oven constituting the top of the flue, an air flue disposed centrally below said oven, the oven bottom having an opening above said air flue, said opening being provided with a removable cover, a damper box provided with a damper disposed below said heating flue to embrace the lower end of said air flue, a burner plate removably supported in said oven in spaced relation to its bottom and with its edges in a spaced relation to the oven walls, said plate being provided with a downturned flange at its front end, a burner mounted on the under side of said burner plate for limited vertical movement and having a centrally disposed downwardly facing tapered coupling member seat, a pilot tube opening through said flange, a gas supply pipe provided with a vertical delivery portion disposed in said air flue, and a coupling member slidably mounted on said delivery portion of said pipe and provided with a conical head adapted to coat with said coupling seat of said burner when the coupling member is elevated.

4. In an oven, the combination of a bottom having an opening therein provided with a removable cover, a damper for controlling the delivery of air through said opening, a burner plate removably supported in said oven, a burner mounted on the under side of said burner plate for limited vertical movement and having a down-

wardly facing coupling member seat, a gas supply pipe provided with a vertical delivery portion below said opening, a coupling member slidably mounted on said delivery portion of said pipe to reciprocate through said opening and coat with said coupling seat of said burner when the coupling member is elevated, a coupling member lever pivotally mounted on said pipe and operatively connected to said coupling member, an actuating lever mounted on said gas supply pipe and operably connected to said coupling member lever, a link connecting said actuating lever to said damper, a gas supply valve, and operating connections from said gas supply valve to said actuating lever.

5. In an oven, the combination of a bottom having an opening therein, a burner plate removably supported in said oven, a burner mounted on the under side of said burner plate for limited vertical movement and having a downwardly facing coupling member seat, a gas supply pipe provided with a vertical delivery portion below said opening, and a coupling member slidably mounted on said delivery portion of said pipe to reciprocate through said opening and coat with said coupling seat of said burner when the coupling member is elevated.

6. In an oven, the combination of a bottom having an opening therein, a burner plate removably supported in said oven in spaced relation to its bottom and with its edges in a spaced relation to the oven walls, said plate being provided with a downturned flange at its front end, a burner mounted on the under side of said burner plate and having a downwardly facing coupling member seat, a pilot tube opening through said flange, a gas supply pipe provided with a vertical delivery portion below said opening, and a coupling member slidably mounted on said delivery portion of said pipe to reciprocate through said opening and coat with said coupling seat of said burner when the coupling member is elevated.

7. A combination stove comprising an oven, a heating flue extending below said oven, the bottom of the oven constituting the top of the flue, said oven bottom having an opening therein, an air flue communicating with said opening, a damper for said air flue, a burner plate removably supported in said oven above said opening, a burner mounted on the under side of said burner plate, a gas supply pipe disposed below said heating flue and provided with a vertical delivery portion disposed in said air flue, a coupling member slidably mounted on said delivery portion of said pipe to be adjusted to and from coacting relation with said burner, an actuating lever operatively connected to said coupling member and to said damper, a gas supply valve, and operating

connections from said gas supply valve to said actuating lever.

8. A combination stove comprising an oven, a heating flue extending below said oven, the bottom of the oven constituting the top of the flue, said oven bottom having an opening therein, an air flue communicating with said opening, a burner plate removably supported in said oven above said opening, a burner mounted on the under side of said burner plate to be positioned above said opening, a gas supply pipe disposed below said heating flue and provided with a vertical delivery portion disposed in said air flue, and a coupling member slidably mounted on said delivery portion of said pipe to be adjusted to and from coacting relation with said burner when the burner is positioned in the oven.
9. In an oven, the combination of a bottom having an opening therein, a burner plate removably supported in said oven in a spaced relation to its bottom and with its edges in a spaced relation to the oven walls, said plate being provided with a down-turned flange at its front end, a burner mounted on the under side of said burner plate, a pilot tube opening through said flange, and an adjustable gas supply connection member adapted to coact with said burner when said member is elevated.

10. The combination in a stove including an oven having an opening in its bottom, of a burner plate removably supported in said oven in a spaced relation to its bottom and with its edges in a spaced relation to the oven walls, a burner mounted on the under side of said burner plate to be positioned above said opening in the oven bottom, a gas supply connection member, and means for adjustably supporting said gas supply connection, mounted on the under side of the stove below the oven so that the said gas connection may be adjusted through said opening into coacting engagement with said burner or retracted from the oven.

11. In an oven, the combination of a bottom having an opening therein, a burner plate removably supported in said oven, a burner mounted on the under side of said burner plate to permit vertical movement having a centrally disposed downwardly facing tapered coupling member seat, and an adjustable gas supply connection pro-

vided with a conical head adapted to coact 55 with said coupling seat of said burner when said member is elevated.

12. In an oven, the combination of a burner plate removably supported in said oven, a burner loosely mounted on the under 60 side of said burner plate, and a gas supply connection supported to be adjusted through the bottom of the oven to engage said burner when said burner plate is in position in the oven or to be retracted from the oven. 65

13. The combination in a stove including an oven having an opening in its bottom, of a burner plate removably supported in said oven, a burner mounted on the under side of the said burner plate, a gas supply 70 connection member, and means for adjustably supporting said gas supply connection, mounted on the under side of said stove below said oven so that the said gas connection may be adjusted through said opening 75 in the bottom thereof into coacting engagement with said burner or retracted from the oven.

14. The combination in a stove comprising an oven having an opening in its bottom, of a burner removably supported in said oven above said opening, a gas supply connection, and means for adjustably supporting said gas supply connection, mounted on the under side of the stove so that the 85 said gas connection may be adjusted through said opening into coacting engagement with said burner and retracted from the oven. 80

15. In a structure of the class described, the combination of a stove provided with a 90 base, an oven provided with a removable burner plate, a supporting rack for said plate pivotally mounted within said base at the rear thereof to receive the burner plate and swing up within the base, and an automatically engaging supporting latch for said rack adapted to be disengaged from the outside of the base. 95

16. In a structure of the class described, the combination of a stove provided with a 100 base, an oven provided with a removable burner plate, and a supporting rack for said plate mounted within said base to receive the burner plate and swing up within the base. 105

In witness whereof, I have hereunto set my hand and seal.

GEORGE W. HOWES. [L.S.]
